DETACHABLE BUTTON

Harry A. Shaffer, East Cleveland, Ohio

Application August 6, 1945; Serial No. 609,236

5 Claims. (Cl. 24—109)

1

This invention relates to buttons, and particularly to ornamental detachable buttons suitable for use on dress garments. The invention is a modified and improved form of the button disclosed in my Letters Patent No. 2,471,589 dated May 31, 1949 and entitled Detachable button.

The primary object of this invention is to provide a detachable button which, when the separable head is removed, leaves a relatively flat supporting base on the textile surface and which base may be pressed without injuring the fabric.

Another object is to provide a device of the type mentioned, the separable parts of which may be firmly locked together when united and which may be simply and easily parted.

A further object is to construct such device out of simple stampings and parts that may be applied to conventional button heads or sewed to ordinary textile fabrics by machinery rather than by hand operations.

Still another object is to provide a detachable button that is mounted on the surface of the supporting fabric with no damage or disfigurement thereto.

These and other objects of the invention will become apparent from a reading of the following description and claims, together with the accompanying drawing, wherein like parts are referred to and indicated by like reference characters and wherein:

Figure 1 is a plan view of the detachable button attached to and engaging pieces of textile fabric;

Figure 2 is a cross-sectional view of the button, taken along the line and in the direction of the arrows 2—2 of the Figure 1;

Figure 3 is a similar view of the button, taken along the line and in the direction of the arrows 3—3 of the Figure 1;

Figure 4 is a plan view of the base member of the button sewed to a piece of textile fabric;

Figure 5 is a cross-sectional view of the base member, taken along the line and in the direction of the arrows 5—5 of the Figure 4;

Figure 6 is a side view of the head member of the button;

Figure 7 is an end view of the same;

Figure 8 is a bottom plan view of the same;

Figure 9 is a side view of the clasp portion of the button head;

Figure 10 is an enlarged plan view of the base member;

Figure 11 is an end view of the base member, taken along the line and in the direction of the arrows 11—11 of the Figure 10;

Figure 12 is an opposite end view of the base member, taken along the line and in the direction of the arrows 12—12 of the Figure 10;

Figure 13 is a side view of the base member,

2

taken along the line and in the direction of the arrows 13—13 of the Figure 10;

Figure 14 is a side view, partly in section, of the base member with a clasp portion partially mounted therein;

Figure 15 is a similar view of the clasp portion fully mounted in the base member;

Figure 16 is an end view of the base member, partly in section;

Figure 17 is an end view of the base member, partly in section, showing the clasp fully mounted therein; and

Figure 18 is a bottom plan view of the base member before being folded.

This invention consists primarily of two major parts: the separable head member, broadly indicated by the character 30, and the fixed anchor body or base member, broadly indicated by the character 40.

10 The separable head member 30 has a button body top surface 31 which may be plain or ornamented as desired. Its bottom or normally concealed surface 32 has a short lateral or diametric channel 33 therein at its center in which the clasp portion 35 is securely mounted.

15 The clasp 35 is made of spring wire and is shaped somewhat like the Greek letter omega. It has a straight central portion that is securely fastened in the aforesaid channel 33 and has two spring fingers 36, the ends of which are bent to form small hooks 37. The hook ends 37 are straight and aligned and their inner ends may be closed as is indicated in the Figure 9 in the drawing. Normally the fingers 36 are spread apart as shown and they are closed only under tension.

20 The anchor or base member 40 is stamped and cut out of thin sheets of resilient stainless metal and is mounted on the underlying fabric 20. The plate portion 41 thereof is substantially square.

25 The edges or corners 42 are trimmed slightly to provide means for sewing the same to the top surface 21 of the textile fabric. The central portion is cut out to form a cross and is also embossed to form a small recess. The leaf portion 51 is folded under the plate portion 41 and has a longitudinal central ridge or boss 53 thereon.

30 The perforations 43 which are punched in the plate member 40 are preferably punched on a bias and are adjacent to the trimmed corners 42.

35 This permits the member to be sewed to the surface 21 of the fabric by means of machine stitches 24. By sewing the base member 40 at the trimmed perforated corners 42, as indicated and stated, the sharp corners or edges thereof are covered and shielded to prevent cutting or tearing of adjacent fabric. It also facilitates pressing since the pressing iron will pass over the base member harmlessly if it is sewed on as stated.

40 Also during cleaning or laundering of the

garment, there is less likelihood of the corners injuring other delicate fabrics.

The central part of the plate portion 41 has a first longitudinal slot 45 and a second lateral slot 46 therein. These two slots cross each other and the second slot 46 is a little shorter than the first slot 45. The part of the plate portion 41 adjacent to the ends of the short slot 46 are embossed or raised, the underside of which forms aligned recesses 47 for the aforementioned aligned finger ends 37, when the head member 30 is mounted. The inside diagonal corners 48 formed by the crossed slots 45 and 46 are spaced apart sufficiently to cause the spring fingers 36 to be tensed or closed when the button is being attached.

The leaf portion 51 is slightly narrower than the plate portion 41 and when folded thereunder, it is between the perforations 43 and does not interfere with the stitches 24 or with the machine sewing of the base member 40 to the fabric 20. Its folded edge 52 is resilient and springy and tends to keep the plate and leaf portions together as shown. The central part of the leaf portion 51 has the heretofore mentioned small ridge or boss 53 which normally rests in the longitudinal slot 45 and lies perpendicularly between the ends of the fingers 36 when the head 30 is attached.

When mounting or attaching the head member 30 to the base member 40, the ends 37 are placed in the slot 45 and on top of the boss 53. The head member is then pressed slightly until the ends 37 clear the bottom surface of the plate portion 41. This separates the plate and leaf portions as shown in the Figures 14 and 16 against the tension of the fold 52. The head member 30 is then given a quarter turn in either direction. Three things then occur. The hooked ends 37 tend to slide off the boss 53 and the spring fingers 36 of the clasp portion 35 are brought together by the constriction formed by the diagonal corners 48 of the plate portion slots. When the head member 30 passes forty-five degrees of the turn, the fingers 36 tend to open or spread again and resume their normal position. When it completes a quarter turn, the hooked ends 37 fit in the aligned recesses 47 and are firmly held therein by the tensional leaf portion 51. The boss 53 then lies perpendicularly between the spread fingers 36.

To remove the detachable head member 30, the operation is reversed. The head may be given a ninety degree turn in either direction and the hooked ends 37 simply removed through the slot 45.

Many advantages are apparent in this improved button. However, certain advantages should be particularly noted. First, the head cannot accidentally fall out or become separated since it is locked in place by three distinct means. The spring fingers are engaged by the corners 48. The leaf 51 retains the ends 37 in the recesses 47 and the boss 53 prevents rotation by engagement with the clasp portion 35. Second, the parts are assembled and held under tension and there is no loose play or rattle between the parts. The button has the feel, when assembled, of a conventional button properly sewed in place and never has a dropped or limp appearance. And third, the clasp portion neatly fits longitudinally in the buttonhole 23 and the buttonhole is not unduly spread or worn to cause an unsightly appearance.

Having thus disclosed the invention in its preferred form, it should be understood that the invention as described and illustrated is not to be construed in a limited sense as there may be other forms or modifications of the invention which may also be considered to come within the scope of the appended claims.

I claim:

1. In a detachable button, a base, comprising, 10 a folded sheet of resilient metal having a top plate portion and a bottom leaf portion, the said top plate portion having crossed slots therethrough and the said bottom leaf portion bearing resiliently against the top plate portion and having a boss thereon normally lying in one of the slots.
2. In a detachable button, a base, comprising in combination, a plate having crossed slots therethrough, rearwardly facing recesses at the ends of one of the said slots, and means for attaching the plate to an underlying material, and a leaf integral with the plate and bearing resiliently thereagainst, the leaf having a boss thereon normally disposed in the other of the said slots.
- 25 3. In a detachable button, a base of the type mountable on the top surface of material, comprising in combination, a top plate having a slot therein, the said top plate also having recesses therein extending crosswise of the said slot, and a bottom leaf bearing resiliently against the top plate and having a boss thereon normally disposed in the said slot and between the aforesaid recesses.
- 30 4. In a detachable button, a base, comprising in combination, a top plate having a slot therein, the said top plate also having recesses therein extending crosswise of the said slot, means for mounting the plate on an underlying material, and a bottom plate integral with the top plate and disposed between the said top plate and the underlying material, the said bottom plate bearing resiliently against the top plate and having a boss thereon normally disposed in the said slot and between the aforesaid recesses.
- 35 5. A separable button, comprising in combination, a head member including a pair of aligned outwardly extending fingers spaced from the back thereof; and an anchor member including a top plate portion attachable to a garment and having crossed slots therethrough, one of the said slots capable of receiving the aforesaid pair of fingers when in a first position and the other of said slots capable of engaging the aforesaid pair of fingers when in a second position, and a bottom 40 leaf portion bearing resiliently against the top plate portion and having a boss thereon disposed in the first aforesaid slot and between the pair of fingers when in their second position.
- 45 60 55 60 65 70 75 80 85 90 95 100
